UNITED STATES PATENT OFFICE.

ALMA NIEBERG, OF BROOKLYN, NEW YORK.

THREAD-CUTTER.

1,134,895.

Specification of Letters Patent.

Patented Apr. 6, 1915.

Application filed October 1, 1913. Serial No. 792,832.

To all whom it may concern:

Be it known that I, ALMA NIEBERG, a citizen of the United States, residing at Brooklyn, in the county of Kings and State of New York, have invented new and useful Improvements in Thread-Cutters, of which the following is a specification.

This invention relates to sewing accessories, and it has particular reference to a simple and improved thread cutting device which will obviate the use of scissors for the purpose of cutting thread, sewing silk and the like, thus saving time and energy.

A further object of the invention is to produce a simple and efficient device capable of being utilized as a weight to hold light articles, such as paper patterns, pieces of dress material and the like in place, but which also serves as a casing and support for a thread cutting blade.

A further object of the invention is to combine the blade with the base in such a fashion that the sharp edge of the blade shall not be exposed except when desired for use, the construction being such that the blade will be guarded when the device is not in use, thereby preventing injury to the blade and danger of incurring accidental cuts.

With these and other ends in view which will readily appear as the nature of the invention is better understood, the same consists in the improved construction and novel arrangement and combination of parts which will be hereinafter fully described and particularly pointed out in the claims.

In the accompanying drawing has been illustrated a simple and preferred form of the invention, it being, however, understood that no limitation is necessarily made to the precise structural details therein exhibited, but that changes, alterations and modifications within the scope of the claims may be resorted to when desired.

In the drawing,—Figure 1 is a perspective view showing a preferred form of the invention, and showing the cutting blade exposed in position for use. Fig. 2 is a top plan view of the same. Fig. 3 is a sectional detail view taken on the line 3—3 in Fig. 2. Fig. 4 is a sectional detail view taken on the line 4—4 in Fig. 2.

Corresponding parts in the several figures are denoted by like characters of reference.

The base 15 of the improved device con-

sists of a block of wood, metal or other material or combination of materials of a specific gravity sufficiently high to enable it to be utilized as a weight. This block or 60 base member may be of any convenient shape; in the drawings an approximately cylindrical block has been shown.

Fitted in the block or base 15 and extending partway across the same in a diametrical position is a blade 16 having a sharp cutting edge 17. Top or cover members 18 are provided with recesses 19 to receive the blade which latter has been shown as being provided with slots 20 for the passage of transverse pins 21, whereby the members 18 are assembled slidably therewith. Each of the members 18 is provided with a notch 22 in the upper side thereof, affording a thumb grip, enabling said members to be conveniently manipulated; one of the members is also provided with a resilient socket 23 to receive a stud 24 carried by the mating member and affording a spring clasp or connection, similar to an ordinary glove 80 clasp, whereby the slidable members may be connected together when moved to a projecting position with respect to the blade so as to expose the latter. The slidable members 18 may be constructed of materials 85 that will enable them to be utilized as pin cushions if so desired.

It will be seen that by moving the members 18 in opposite directions apart from each other the blade 16 will be uncovered, thus enabling it to be utilized for cutting thread and the like. When it is not desired to expose the blade for present use, the members 18 may be moved toward each other and secured together by the interengaging snap members 23, 24. The device will then present the appearance of an ordinary pin cushion and may be utilized as such.

It will be understood that while I have 100 shown and described specific forms of my invention, other modifications may be resorted to within the scope of the appended claims.

Having thus described the invention, what 105 is claimed as new, is:—

1. A device of the class described comprising a relatively heavy base block, a sharp-edged blade projecting upwardly from the top face thereof, said blade having longitudinal slots, and cover members having blade engaging recesses, said cover members

having pins extending transversely there-through and slidably engaging the slots in the blade.

2. A device of the class described comprising a relatively heavy base block, a sharp-edged blade projecting upwardly from the top face thereof, said blade having longitudinal slots, and cover members having blade engaging recesses, said cover members having pins extending transversely there-

through and slidably engaging the slots in the blade, and said cover members being provided on their opposed faces with inter-engaging fastening members.

In testimony whereof I affix my signature 15 in presence of two witnesses.

ALMA NIEBERG.
